US00D991464S

(12) **United States Design Patent** (10) **Patent No.:** **US D991,464 S**
Unnava et al. (45) **Date of Patent:** **** Jul. 4, 2023**

(54) **JOINT STABILIZATION ELBOW SLEEVE**

(71) Applicant: **Better Walk, Inc.**, Atlanta, GA (US)

(72) Inventors: **Partha Sarathy Unnava**, Atlanta, GA (US); **Tyler Jack Prescott Harmon**, Decatur, GA (US)

(73) Assignee: **BETTER WALK, INC.**, Atlanta, GA (US)

(**) Term: **15 Years**

(21) Appl. No.: **29/745,480**

(22) Filed: **Aug. 6, 2020**

(57) **CLAIM**

The ornamental design for a joint stabilization elbow sleeve, as shown and described.

DESCRIPTION

FIG. 1 is a perspective view of an exemplary joint stabilization elbow sleeve;

FIG. 2 is a front view of an exemplary joint stabilization elbow sleeve;

FIG. 3 is a rear view of an exemplary joint stabilization elbow sleeve;

FIG. 4 is a right side view of an exemplary joint stabilization elbow sleeve;

FIG. 5 is a left side view of an exemplary joint stabilization elbow sleeve;

FIG. 6 is a top view of an exemplary joint stabilization elbow sleeve; and,

FIG. 7 is a bottom view of an exemplary joint stabilization elbow sleeve.

The broken lines in the drawings are for the purpose of illustrating portions of the joint stabilization elbow sleeve and form no part of the claimed design.

1 Claim, 7 Drawing Sheets
